(57) **CLAIM**

The ornamental design for a desktop phone holder as shown and described.

DESCRIPTION

FIG. 1 is a top perspective view of a desktop phone holder showing my new design.

FIG. 2 is a front view thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a right side view showing a state of use with a phone.

FIG. 9 is a rear view showing a state of use with a phone; and,

FIG. 10 is a right side view of FIG. 4 showing another state of use with a phone.

Broken lines and adjacent unshaded areas in FIG. 7 illustrate portions of the desktop phone holder that form no part of the claimed design. Additional broken lines in FIGS. 8, 9, and 10 illustrate environmental subject matter and form no part of the claimed design.
